FIRE-EXTINGUISHING BOMB.

1,149,975.

Specification of Letters Patent.

Patented Aug. 10, 1915.

Application filed January 23, 1915. Serial No. 4,049.

To all whom it may concern:

Be it known that I, ALBERT L. COLE, a citizen of the United States, residing at Auburndale, in the county of Middlesex and State of Massachusetts, have invented a new and useful Improvement in Fire-Extincting Bombs, of which the following is a specification, reference being had therein to the accompanying drawings.

This invention relates to an automatic fire extinguisher and more particularly to a fire extinguishing bomb which is adapted to explode and scatter the fire extinguishing fluid when the temperature in the room or space where the bomb is located reaches a predetermined point.

Heretofore it has been customary to employ what are known as sprinkler systems consisting of an arrangement of pipes communicating with a source of supply of fire extinguishing fluid, generally water, and provided with a series of outlets closed by fusible plugs, so that when a fire occurs and the temperature reaches a predetermined point the plug is melted and the fire extinguishing fluid allowed to flow out. This system is open to the objection that even after the fire is extinguished, the sprinkling of the fire extinguishing fluid continues until the system is shut off at some central point, thereby frequently entailing a heavy loss or damage from water. In addition to the foregoing objection, such systems require an elaborate arrangement of pipes and valves and are expensive to install and to maintain.

The main object of the present invention is to provide a fire extinguishing device of simple and low cost of construction which will explode automatically to scatter fire extinguishing fluid over the fire when the temperature in the room or space where it is located reaches a predetermined point.

Another object of the invention is to provide a device which is entirely self-contained and which therefore may be installed wherever required either singly or in groups and either on ceilings or on walls.

A further object of the invention is to provide an automatic fire extinguisher which will not freeze at low temperatures, so that it may be used in unheated buildings where the ordinary system employing water would freeze.

Other and further objects of the invention will appear hereinafter.

In the accompanying drawings illustrating in preferred form an embodiment of the present invention, Figure 1 is a side elevation, partly in section, of my fire extinguishing bomb shown as applied to a ceiling, Fig. 2 is a side elevation of the same shown as applied to a bracket secured to a partition wall; and Fig. 3 is a bottom plan view of the bomb plate.

In the preferred embodiment of the present invention the receptacle for containing the fire extinguishing compound is shown in the drawings as a depressed globular glass bottle or bomb 5, of sufficient fragility to break when acted upon internally by a predetermined expansive force, and is provided with a neck 6 threaded externally. The orifice of the neck of the bottle is closed and made air tight by a cork stopper 7. A plate 8, having a depending central portion 9 threaded internally for the reception therein of the neck of the receptacle, is adapted to be secured by means of screws 10 to the ceiling 11 of the room in which the extinguisher is to be used, or to a bracket 12 when the extinguisher is to be secured to the partition wall 13, and serves to maintain the receptacle in operative position. A metal screen or net 14 entirely surrounding the receptacle 8 is suspended from the bomb plate by hooks 15 made of soft metal, which may be readily brought into position for insertion through the loops 16 on the net and then bent up against the plate to prevent the hoops from slipping over the ends of the hooks, as is shown in Figs. 1 and 2. This net serves to prevent the glass of the receptacle, when it is broken, from falling to the floor, and also protects the bomb from injury at ordinary times.

The fire extinguishing compound may be of any usual and well known composition suitable for the purposes of this invention. It must, however, besides possessing those properties which are incident to fire extinguishing compounds in general, be possessed of the following properties. It must be readily volatilizable and when it has been converted into a gaseous state it must be heavier than the atmosphere so that it will settle. Its ready volatilization causes it to exert a strong expansive force upon the re-

ceptacle in which it is confined when it is subjected to heat. For ordinary purposes the strength of the receptacle and the expansive force of the fire extinguishing compound must be such that when the temperature of the room in which the receptacle is placed has reached 150 degrees Fah., the expansion of the compound will burst the receptacle and be dispersed into the room.

10 Moreover the fire extinguishing compound must be of such nature that when the receptacle or bomb is burst and the compound is scattered or dispersed into the room, if it is not entirely converted into gas by the 15 heat arising from the fire, that part of it which falls onto the fire in the liquid form will then be converted into gas so that whether the fire extinguishing compound be converted into gas immediately upon the 20 bursting of the bomb or upon the compound reaching the fire in a liquid state the heat will cause it to form a thick heavy gaseous blanket somewhat heavier than the atmosphere of the room and, therefore, capable of 25 forming a blanket impenetrable by the flames of the fire and thereby acting to prevent the flames from reaching the oxygen in the air so that the fire will be suffocated and extinguished.

30 Any fire extinguishing fluid having the foregoing characteristics may be used in connection with my invention and one such fluid which I found satisfactory for this purpose is acetylene tetrachlorid the chemical formula of which is $C_2H_2Cl_4$.

35 The operation of the automatic fire extinguishing bomb is as follows: The bombs are secured to convenient and preferred parts of the room it is desired to protect against 40 fire. Now, upon the outbreak of a fire the temperature of the room in the immediate vicinity of the fire rises and inasmuch as air is a very poor conductor of heat, the air immediately above the fire rises perpendicularly more readily than it spreads laterally, therefore, the bomb more nearly above the 45 spot where the fire is, will be brought into action first and when the temperature around about the bomb has reached about one hundred and fifty degrees Fah. the expansive force of the fire extinguishing compound as it attempts to vaporize will cause the receptacle to break and the compound to be dispersed into the air. The heat will instantly 50 convert a portion of the escaping compound into a heavy gaseous blanket, which will settle and which together with the gaseous blanket formed by the portion of the compound which falls onto the fire in a liquid state, will suffocate and extinguish the fire. If the fire is a small one and the gaseous 55 blanket settling down over it is sufficient to extinguish it, only one of the fire extinguishing bombs will have been brought into action and the damage will be limited to the

spot covered by the blaze. In this respect it will be seen that the present invention has great advantages over a water system in which, when one of the units has been brought into action by the heat, the water continues to flow from the unit until it is turned off at the central reservoir, often causing far more damage than the fire itself. Moreover considerable waste in water is eliminated, which in itself is no inconsiderable saving. When the receptacle containing the compound breaks, it is prevented from falling to the floor by the metal screen whose mesh is fine enough to prevent the escape of any but very small particles of glass, so that the danger of falling glass is eliminated.

It is to be observed that inasmuch as the fire extinguishing bomb is self-contained and individual it can consequently be used in 85 very small apartments, as a closet, for example, unconnected with a main system. It will, therefore be seen that the sprinkler is suitable for use in private dwellings and residences. This individuality of the bomb, 90 however, and adaptability for use in small apartments, does not prevent it from forming a unit of an aggregation of bombs sufficient in number to replace a large fire extinguishing system, so that if the fire is of 95 sufficient size, all the bombs may be brought into play in unison.

Another advantage possessed by the automatic fire extinguishing bomb embraced by this invention lies in the very low freezing point of fire extinguishing compounds. This incidental property of fire extinguishing compounds in general, and therefore of the compound used in the furtherance of the objects of this invention enables the 100 bomb to be employed for protection against fire in buildings where a water springer system is useless in cold weather; and also dispenses with the necessity and consequent expense of maintaining sufficient warmth in 105 other buildings to prevent the freezing of the water sprinkler system, in order to insure proper automatic fire protection.

Having thus described my invention, what I claim is:—

1. An automatic fire extinguisher comprising a highly frangible sealed container having a compound confined therein, of a character when liberated to extinguish fire, said compound being expansible under abnormal heat to a degree capable of shattering the container and disseminating itself into spray or gas covering a large area, substantially as and for the purpose described.

2. An automatic fire extinguisher comprising a container, and a compound therein of a character when liberated to extinguish fire, said compound being rapidly expansible under an abnormal rise of temperature outside of the container to compel shattering

of the container thereby and dispersing of the compound.

3. A fire extinguisher comprising a frangible container having a fill opening, means for closing said fill opening, means for mounting the container in place whereby the closure is held in sealed relation to the container, and a fire extinguishing compound in the container of a character to expand 10 under heat and shatter the body of the container.

4. A fire extinguisher comprising a frangible container having a fill opening, means for closing said fill opening, means for supporting said container in place whereby the said closing means are held in sealed relation to the container, and a fire extinguishing compound in said container of a character to expand under abnormal heat to shatter 20 the body of said container and to disseminate itself in the form of a spray or gas over a relatively large area.

5. In a fire extinguisher, a support having a depending threaded central portion, a container for a fire extinguishing compound, a stopper for said container, and a threaded portion on the closed end of the container adapted to engage the threaded portion of the support, a part of the support overlying 30 the stopper to hold the latter in place.

6. In a fire extinguisher, a container having a fill opening within a coupling portion, a support having a complementary coupling portion, and a closure for the fill opening held in place by engagement of the support therewith when the parts are coupled.

7. In a fire extinguisher, a container hav-

ing a fill opening within a coupling portion, a support having a complementary coupling portion, a closure for the fill opening held in place by engagement of the support therewith when the parts are coupled, the coupling portions comprising a threaded stem on the container and a correspondingly threaded outwardly projecting portion on 45 the support closed at the base thereof by a part of said support.

8. In a fire extinguisher, a container having a fill opening within a coupling portion, a support having a complementary coupling 50 portion, a closure for the fill opening held in place by engagement of the support therewith when the parts are coupled, the coupling portions comprising interlocking hollow stems one fitting within the other, and 55 the outer stem portion being closed at its base by a part of the support.

9. In a fire extinguisher, a support having a hollow receiving part, a container for a fire extinguishing compound having a stem adapted to interlock with said receiving part, said stem having a fill opening, and a closure for the fill opening adapted to be held in place as an incident to the interlocking of the stem and receiving portions, substantially as described.

In testimony whereof, I hereunto set my hand in the presence of two subscribing witnesses, this the twelfth day of January, 1915.

ALBERT L. COLE.
